TOTALIZING AND RECORDING APPARATUS

Otto P. Haegle and Lee C. Northcliffe, Chicago,
Ill., assignors to Streeter-Amet Company, Chi-
cago, Ill., a corporation of Illinois

Application April 29, 1936, Serial No. 76,894

3 Claims. (Cl. 235—60)

This invention relates to totalizing and recording devices, and among other objects aims to adapt an adding machine for certain recording functions which do not influence totalization.

8 The invention may be readily understood by reference to one embodiment thereof shown in the accompanying drawings.

In said drawings:

Fig. 1 is an elevation of weighing apparatus 10 having the aforesaid recording and totalizing features;

Fig. 2 is a plan section taken on the plane 2—2 of Fig. 1;

15 Fig. 3 is an elevation of the adding sectors and accumulator pinions of a standard adding machine;

Fig. 4 is a sectional elevation taken on the plane 4—4 of Fig. 3;

20 Fig. 5 is a fragmentary elevation taken on the plane 5—5 of Fig. 4, showing certain accumulator pinions shifted out of mesh with the adding sectors;

25 Fig. 6 is a plan section taken on the plane 6—6 of Fig. 4 showing normal or operating adjustment wherein certain of the accumulator pinions for higher denominational order are out of mesh with their adding sectors;

30 Fig. 7 is a view similar to that of Fig. 6, showing the relation of the aforesaid pinions and their adding sectors during the recording of a total or sub-total;

Fig. 8 is an elevation on an enlarged scale showing the mechanism for shifting certain accumulator pinions for the recording of totals and 35 sub-totals;

Fig. 9 illustrates a sample piece of record tape; and

Fig. 10 is a sectional elevation of a detail of the shifting mechanism, taken on the plane 10—10 of Fig. 6.

40 According to the present invention, it is possible to utilize surplus or idle denominational orders and the printing mechanism associated therewith for recording purposes, without carrying the same into the totalizing or accumulating mechanism. For example, if, in the normal use of an adding machine whose keyboard has nine columns of keys, only the first or lower five denominational orders are employed (i. e., if no 45 larger than five-digit numbers are introduced into the adding machine), the present invention makes it possible to use the surplus or higher denominational orders and their printing mechanism to record symbol numbers, etc. without carrying such numbers into the accumulator. Nev-

ertheless, the entire accumulator capacity of the machine may be employed in accumulating and recording totals and sub-totals. A further example is that disclosed in Basquin and Haegle Patent No. 2,131,683, wherein the lower denominational orders (the first five in that case) of the adding machine are employed to record the net weight of loads on the scale and the higher denominational orders are employed to record (but not to totalize) the tare weights.

5 There are, of course, many other uses for the recording mechanism represented by the surplus denominational orders. In weighing mine cars, the surplus orders may be used to record the number of the miner to be credited for the load 10 in the car. In batching apparatus wherein the ingredients comprising the batch are weighed, the surplus orders may be used to record a number symbol (representing the material weighed) 15 opposite its weight. These illustrations will serve 20 to suggest the fields of uses for the invention.

The invention is here embodied in a standard key-set adding machine of simple construction, such as that disclosed in Barrett Patents Nos. 1,784,862, 1,811,840, 1,925,089, 1,935,609 and 25 1,949,446. As will be apparent, the invention is however, capable of embodiment in many other designs of adding machines and without necessitating substantial modification or alteration of the standard apparatus.

30 As illustrating one use of the present adding machine, the latter may be embodied in a weighing and recording apparatus such as that shown in said Patent No. 2,131,683. This is illustrated somewhat diagrammatically in Fig. 2 wherein the pertinent elements of the apparatus of said patent are diagrammatically represented as follows: 35 11 is the dial shaft movable responsively to the load on the scale, on which shaft are fixed the conventional pointer 12 and the step cams 13, 14 and 15. As explained in said patent, the latter step cam serves in conjunction with the step cam 40 16 to set the several digit slides for the lower five denominational orders of the adding machine. It will be understood by a reference to said patent 45 that the dial shaft and step cams are rotated responsively to the load on the scale to a position representing the weight of the load on the scale. Further it will be understood that the step cams represent one means, equivalent to the 50 keys on the adding machine keyboard, for setting the digit slides of the adding machine in position to carry the appropriate number on the type segment into printing position. It will be noted that the digit slides are equipped with ex- 55

tension fingers 19 which project from the adding machine and are provided with extremities which engage the several step cams.

The digit slides 20 representing the higher or surplus denominational orders are set in any desired way to bring the proper digits on the type segments into printing position. Such setting means may be the usual keys on the keyboard, or, as here shown, a step cam 21, which in this instance serves to record the tare weight on the scale. The digit slides 20 are also provided with extension fingers 22 which engage the several series of steps on the step cam 21. If the digit slides be key-set, they need not be provided with the extensions 22.

Where, as here, the digit slides are set not by keys but by extensions on the digit slides themselves, it is not essential that the adding machine be provided with a keyboard (excepting totalizer and accessory keys), but the presence of the keyboard would not interfere with the operation of the apparatus. Where the surplus denominational orders are manually key-set, the machine should, of course, be provided with a keyboard covering all key-set orders.

As shown in Fig. 1, the adding machine is tilted from its normal position, so that the line of travel of the digit slides and their extensions intersect the axis of dial shaft 11.

The aforesaid surplus denominational orders are made independent of the accumulator mechanism by relatively shifting the accumulator pinions 25 and their adding sectors or accumulator pinion driving racks 26 to non-meshing relationship, thereby allowing the adding sectors 26 and their type segments 27 to be moved independently of the accumulator and without carrying into the accumulator the digits recorded by these type segments. This is advantageously effected in the present construction by substituting for the usual accumulator pinions of the lower denominational orders, wider pinions 28 which allow the pinions 25 to be shifted laterally into and out of mesh with their adding sectors 26 without disturbing the normal intermeshing relation between the adding sectors 26 of the lower denominational orders and their pinions. This arrangement makes it possible to shift the accumulator shaft 31 laterally to mesh and unmesh pinions 25 and adding sectors 26 while maintaining the normal relation between pinions 28 and their adding sectors 29 (see Figs. 6 and 7).

While the illustrative accumulator mechanism is of a conventional type, it may be found illustrated and described in greater detail in said Barrett patents. For example, the accumulator pinions 25 and sectors 26 herein correspond respectively to the accumulator pinions 26 and sectors 5 in Figs. 2 and 5 of said Barrett Patent No. 1,949,446, and to the pinions 108 and gear racks 107 in Figs. 2, 16, 17 and 18 of said Barrett Patent No. 1,811,840.

To use the higher denominational orders for independent recording purposes (not involving totalization), the accumulator shaft 31 is shifted laterally to unmesh accumulator pinions 25 and their adding sectors 26. Any record made by the digits on the type segments carried by sectors 26 does not, therefore, influence the total. On the other hand, the lower denominational orders represented by adding sectors 26 have their normal relation with the accumulator which serves to accumulate totals of numbers introduced by the

lower denominational orders in the usual manner and to the full capacity of the accumulator.

To record a total or sub-total it ordinarily requires the use of some or all of the higher denominational orders, making it necessary to employ the adding sectors 26 and their type segments. In that event, the accumulator shaft 31 is shifted laterally to place sectors 26 in mesh with their pinions 25. The latter sectors are, therefore, controlled by the accumulator in the usual way to print totals and subtotals.

An illustrative form of accumulator shifting mechanism is particularly illustrated in Figs. 6 to 8. As shown in Fig. 6, the pinions 25 and their sectors 26 are held in unmeshed relation by a slideable cam block 35 having a recess 36 with an inclined cam surface leading therefrom. For the recording of totals and sub-totals, cam block 35 is shifted to bring its recess 36 into registry with accumulator shaft into which recess the latter is moved by flat spring 37, bringing pinions 25 and their sectors into mesh (see Fig. 7). Cam block 35 is advantageously controlled by the total and sub-total keys 38 and 39 respectively. As here shown, (Fig. 8) the totalizer cam 41 is provided with a notch 42 adapted to engage pin 43 carried by cam block 35. When the total cam 41 is operated either by the total or sub-total keys, it engages pin 43 and moves the same in the direction of the arrow adjacent the pin (Fig. 8) to move notch 36 into registry with accumulator shaft 31 (Fig. 7), bringing about the intermeshing of pinions 25 and their sectors 26. Thereupon the actuation of the adding machine operating lever 44 causes the accumulator to operate the type segments to register the total accumulated therein and the printing mechanism to print such total on the tape or other record 45. To clarify illustration, (Fig. 8) the totalizer key lever and totalizer cam 41 have been more heavily shaded to bring out the train of mechanism by which the cam block 35 is operated as aforesaid. Sub-total lever 39 also similarly operates totalizer cam 41 and block 35.

Upon giving the operating handle 44 its return movement (which is opposite that of the arrow on the handle), a pin 46 carried by the accumulator cam 47 (Figs. 6 and 8) engages slide 48 connected to pin 43, moving the latter and cam block 35 (to the position shown in Fig. 6) to shift accumulator shaft and unmesh pinions 25 and sectors 26. The accumulator cam 47 has been more lightly shaded to enable it to be clearly distinguished from totalizer cam 41 (Fig. 8).

As shown in Fig. 10, cam block 35 is provided with forked and slotted ends 49 and 51 which straddle pins 52 and 53 by which the block is guided for sliding operation.

It will be understood that in the present type of adding machine, the only difference between sub-total operations and totalizing operations is that in the latter the accumulator pinions instead of being restored to the position representing the accumulated total are cleared. The mechanism for shifting the accumulator and its pinions into and out of mesh with the adding sectors for the foregoing purposes is well known and need not be described.

To compensate for the lateral displacement or shifting of the accumulator pinions 25, the final or carrying teeth 54 on the respective sectors 26 are increased in width so that they will engage the sectors in their normal operation of "carrying" from one accumulator pinion to the next. (See Figs. 4 and 5.) The manner of "carrying" 75

from one accumulator pinion to the one of next higher denominational order is illustrated in greater detail in Fig. 2 of said Barrett Patent No. 1,949,446, in Fig. 3 of said Barrett Patent No. 1,935,609, and in Fig. 16 of said Barrett Patent No. 1,811,840. Figs. 4 and 5 in the present application illustrate simply the details herein involved, other details having been omitted.

Ordinarily, the adding sectors prevent accidental shifting or displacement of the accumulating pinions. The unmeshed pinions 25 which are not thus held against accidental shifting are here shown provided with means which impose a slight friction or brake on the sectors and therefore prevent their accidental displacement. Such means are here shown in the form of flat leaf springs 55 which engage the edges of the pinion discs 56. Their sector of engagement with the discs 56 is made long enough to span the locking notches carried by each disc 56 to avoid catching in such notches.

In Fig. 9 is illustrated a specimen record tape or sheet wherein the digits in the first three surplus columns represent a tare weight or some other numbered symbol which is not carried into the total. It is desirable that the surplus digits be easily distinguishable from the others. Those for recording the tare are here distinguished by underlining and the last or highest column which may be employed for number symbols are distinguished by subjacent dots. The means employed for distinguishing the non-adding from the adding digits may, of course, be greatly varied. The five lower denominational orders to the right represent the digits (in this case the net weight records) which are carried into the accumulator and thus totalized. The line of digits 57 represents a sub-total of the above five columns of digits and carries the customary symbol 58 (S in this case) to indicate a sub-total. The line of digits at 59 represents a total which is characterized by the symbol 61. It will be noted that the digits in the totals and sub-totals may carry into the higher denominational orders in the ordinary way, i. e., the entire capacity of the accumulator and the printing segments are available for accumulating and printing totals and sub-totals. In most types of adding machines, the mechanism will accumulate and print a total which may contain one more digit (in this case ten in all) than the number of banks of keys.

Obviously the invention is not limited to the details of the illustrative construction since these may be variously modified. Moreover, it is not indispensable that all features of the invention be used conjointly since various features may be used to advantage in different combinations and sub-combinations.

Having described our invention, we claim:

1. In an adding machine the combination comprising an accumulator having pinions for the several denominational orders, accumulator pinion driving racks meshing with the respective pinions, a plurality of said pinions for the lower denominational orders being wider than those for the higher orders to permit said accumulator to be shifted longitudinally to unmesh the higher order pinions, the lower order pinions remaining in mesh, and means for shifting said accumulator to move said higher order pinions in and out of mesh with their driving racks. 20

2. In an adding machine, the combination comprising an accumulator having pinions for the several denominational orders, accumulator pinion driving racks whose faces mesh with those of the respective pinions, certain of the meshing faces between the racks and pinions for the lower denominational orders being wider than those for the higher orders to permit relative longitudinal shifting between the racks and pinions to unmesh those of the said higher orders while maintaining those for the lower orders in mesh, and means for effecting relative shifting between said racks and pinions to mesh and unmesh those for the said higher orders. 25

3. In an adding machine, the combination comprising adding sectors for a series of denominational orders, an accumulator having corresponding accumulator pinions adapted to mesh with the respective sectors, means for relatively longitudinally shifting a higher order accumulator pinion and its adding sector to unmesh the same and for maintaining the lower order accumulator pinions and their adding sectors in normally meshing relationship, and means operable upon the taking of a total for temporarily effecting relative shifting between said higher order pinion and its sector longitudinally to restore meshing relationship in order to make the full capacity of the accumulator available for exhibiting a total. 45
